UNITED STATES PATENT OFFICE.

ARTHUR R. HAVENER, OF WALTHAM, MASSACHUSETTS, ASSIGNOR TO JUDSON L. THOMSON M'FG CO., A CORPORATION OF MASSACHUSETTS.

HOPPER FOR FEEDING TWO-PRONGED RIVETS.

1,179,916.

Specification of Letters Patent. Patented Apr. 18, 1916.

Application filed February 15, 1915. Serial No. 8,162.

To all whom it may concern:

Be it known that I, ARTHUR R. HAVENER, a citizen of the United States, residing at Waltham, in the county of Middlesex and State of Massachusetts, have invented new and useful Improvements in Hoppers for Feeding Two-Pronged Rivets, of which the following is a specification.

This invention relates to an improved hopper especially designed to be used in connection with feeding two-pronged rivets one by one from a mass of said rivets to a raceway.

The invention consists in the combination and arrangement of parts set forth in the following specification and particularly pointed out in the claims.

Referring to the drawings: Figure 1 is a plan view of my improved hopper. Fig. 2 is a side elevation, partly broken away and shown in section. The hopper when in use is inclined on the line *a—a*. Fig. 3 is a sectional elevation taken on line 3—3 of Fig. 1 and broken away to save space in the drawings. Fig. 4 is a sectional plan taken on line 4—4 of Fig. 2 and broken away to save space in the drawings. Fig. 5 is a detail section taken on line 5—5 of Fig. 4. Fig. 6 is a sectional plan taken on line 6—6 of Fig. 3. Figs. 7 and 8 are detail sectional plans taken on line 4—4 of Fig. 2 illustrating the different positions of a rivet as it is fed to the raceway. Fig. 9 is a sectional elevation taken on line 9—9 of Fig. 1. Fig. 10 is a sectional elevation taken on line 10—10 of Fig. 4. Fig. 11 is a detail section taken on line 11—11 of Fig. 7. Fig. 12 is a detail section similar to Fig. 5 of a modified form of hopper casing.

Like numerals refer to like parts throughout the several views of the drawings.

In the drawings, 15 is the hopper consisting of a casing 16 and a rotary member 17. The casing 16 has a cylindrical wall 18 and a conical shaped bottom 19. At the base of the cylindrical wall 18 is a shelf 20, preferably arranged at an angle of ninety degrees to the wall 18 and forming a support for the heads of the rivets as they are fed around in the hopper toward the raceway 21. The bottom of the hopper is inclined downwardly from said shelf. An annular flange 22 extends part way around the inner face of the wall 18, there being a space 23, constituting a slot, between said

annular flange and the shelf 20 into which a portion of the head of a rivet 24 may project, as illustrated in Fig. 5. Said annular flange terminates at one end thereof at 25, as seen in Fig. 1, and at the opposite end it 60 terminates at 26. It will be seen that the inner edge 27 of said annular flange 22 performs the function of guiding the legs of the rivet and as said flange is rigidly fastened to or may be made integral with said 65 wall it will be evident that the inner edge of said flange constitutes, in effect, a portion of the inner face of the wall of said casing. The raceway 21 consists of a bottom plate 28, two side walls 29 and two 70 cover flanges 30 which are separated by a slot 31. It will be seen that the bottom of the raceway 21 forms a continuation of and is substantially flush with the top of the shelf 20. A slot 42 is provided at the bottom of the wall 18 on the opposite side of the raceway from that which intersects the flange 22, the bottom of said slot 42 forming a portion of the shelf 20 where it extends beyond the raceway 21. The slot 42 is 75 substantially of the same height as the slot 23 and serves the same function, namely, to form a space to receive a portion of the heads of the rivets as they lie on the shelf 20 preparatory to passing down the raceway 21. 80

The head of the rivet as it passes down the raceway is inclosed within a chamber 32 formed by the bottom, side walls and cover flanges of said raceway, while the prongs 90 project from said chamber through the slot 31. The raceway 21 extends through the cylindrical wall 18, entering the interior of the casing 16 at 33, and it will be noted that the end 26 of the annular flange 22 forms 95 a part of one side of said raceway where the same leads out of the casing, said side wall 26 intersecting the edge 27 of the annular flange at an acute angle, as illustrated in Figs. 4, 7 and 8. The end 26 of said 100 flange 22 which forms a portion of one wall of the raceway 21 extends inwardly beyond the opposite wall of said raceway, as clearly seen in Fig. 4, so that the rivet may have room to turn its prongs and allow said 105 prongs to enter the slot 31 of said raceway. The shelf 20 is made narrower adjacent to the entrance to said raceway, as illustrated in Figs. 3 and 4, so that any of the rivets which do not enter the raceway may fall 110

back into the bottom of the hopper. The rotary member 17 has a series of flexible fingers 34 fast thereto and projecting downwardly from said rotary member adjacent to the flange 22. These flexible fingers are preferably made of wire wound in the form of spiral springs and act as a means to push the rivets along the shelf 20 and into the raceway 21. Said member 17 is given a rotary movement by means of suitable gearing 35 fast to a shaft 36 to which said rotary member 17 is rigidly fastened.

In order to release the rivets and allow them to slide downwardly into the raceway 21, the fingers 34 are arranged to engage a cam 37 (shown in Figs. 3 and 4), said cam commencing at 38 adjacent to the point where the raceway enters the casing 16 and terminating at 39 (Fig. 4).

While it is more convenient, in the manufacture of the hopper, to make the flange 22 as shown in the drawings, it will be evident that without departing from the spirit of my invention said flange might be continued to the top of the casing, for it is the inner face of said flange which guides the prongs of the rivets and the flange forms a cover over the heads of the rivets where they project therebeneath to prevent one rivet from piling on top of another. In Fig. 12 I have illustrated such a modified form of my invention in which 43 is the casing wall, 44 the shelf, 45 the slot above the shelf and beneath the casing wall and 46 the flange extending from the slot 45 to the top of the casing wall 43. The flange 22 or the flange 46 may be made integral with the casing wall without departing from the spirit of my invention, but it is preferable to have said flange made in a separate piece on account of the ease of manufacturing the same.

The operation of the hopper hereinbefore specifically described is as follows: Said hopper is positioned when in use with the casing standing at an angle of 45°, as illustrated by the broken line $a-a$ of Fig. 2. Thus all of the parts are set at angles of 45° to a vertical plane and the rivets will lie in mass in the left hand side of the hopper as viewed in Figs. 1, 2, 3, and 4 of the drawings. A rotary motion is imparted to the member 17 and the flexible fingers 34 engage the rivets and move them along the shelf 20 with their heads resting on said shelf and their prongs resting against the guiding edge 27 of the annular flange 22, as illustrated in Fig. 4. Said rivets are carried beyond the raceway in some instances and assume the positions illustrated in Fig. 4, with a portion of their heads projecting into the slot 42 and their prongs resting against the inner face of the casing wall. These rivets in the relative positions illustrated in Fig. 4, it will be seen, are prevented from passing down the raceway by the rivet 24'

which is just about to pass the entrance to the raceway, but said rivet 24' upon continued motion of the rotary member 17 and the flexible fingers 34 thereon will be pushed along in the direction of the arrow (Fig. 4) 72 and this will cause the rivets which are resting on the shelf 20 on the opposite side of the raceway from the rivet 24' to be pushed along said shelf a slight distance until the rivet 24' can pass around the corner of the 75 flange 22 adjacent to the raceway and into said raceway. Said rivet will at such a time be partially rotated and assume substantially the three different positions illustrated in Fig. 6. As soon as the rivet 24' begins to 80 slide down the raceway the other rivets which are located along the shelf on the opposite side of the raceway from the end of the flange 22 will slide down the raceway following the rivet 24'. As the fingers 85 34 pass the end of the raceway they will encounter the cam 37 and will be moved inwardly toward the center of the hopper, thus disengaging the rivets which have been pushed along to the entrance to the raceway 90 and allowing them to slide down said raceway, it being understood that the raceway extends at an angle of about 45° so that said rivets will slide down the raceway as soon as they are in alignment with it and released 95 by said fingers.

Having thus described my invention, what I claim and desire by Letters Patent to secure is:

1. A hopper for feeding a two-pronged rivet having, in combination, a casing with a cylindrical wall and a bottom comprising a shelf extending at an angle to said wall and forming a support for a rivet head and a central portion inclined at an angle to said shelf, a raceway leading out of said casing at the bottom of said cylindrical wall, an annular flange extending partly around the inner face of said cylindrical wall at a distance from the bottom of said wall slightly greater than the depth of the head of said rivet, the termination of said flange at one end thereof forming part of one side of said raceway where the same leads out of said casing, and means constructed and arranged to engage said rivet and push it along said casing and into said raceway, with a portion of its head beneath said flange and with one of said prongs resting against the inner edge of said flange.

2. A hopper for feeding a two-pronged rivet having, in combination, a casing with a cylindrical wall and an inclined bottom, a raceway leading out of said casing at the bottom of said cylindrical wall, an annular flange extending partly around the inner face of said cylindrical wall at a distance from the bottom of said wall slightly greater than the depth of the head of said rivet, the termination of said flange at one end there-

of forming part of one side of said raceway where the same leads out of said casing, means constructed and arranged to engage said rivet and push it along said casing, 5 with a portion of its head beneath said flange and with one of said prongs resting against the inner edge of said flange and means adjacent to the entrance to said raceway constructed and arranged to move 10 said pushing means out of engagement with said rivet.

3. A hopper for feeding a two-pronged rivet having, in combination, a casing with a cylindrical wall and a bottom, a shelf 15 forming a part of said bottom at the base of said wall arranged at an angle thereto and forming a support for a rivet head, the bottom of said hopper being inclined downwardly from said shelf at an angle 20 thereto, an annular flange extending partly around the inner face of said wall, there being a space between said flange and shelf into which a portion of the head of said rivet may project, the inner edge of said 25 flange constituting a guide for the prongs of said rivet, and a raceway leading out of said hopper, the bottom of said raceway being a continuation of the top of said shelf and one side of said raceway intersecting 30 the inner edge of said flange.

4. A hopper for feeding a two-pronged rivet having, in combination, a casing with a cylindrical wall and a bottom, a shelf forming a part of said bottom at the base 35 of said wall arranged at an angle thereto and forming a support for a rivet head, the bottom of said hopper being inclined downwardly from said shelf at an angle thereto, an annular flange extending partly around 40 the inner face of said wall, there being a space between said flange and shelf into which a portion of the head of said rivet may project, the inner edge of said flange constituting a guide for the prongs of said 45 rivet, a raceway leading out of said hopper, the bottom of said raceway being a continuation of the top of said shelf and one side of said raceway intersecting the inner edge of said flange, said shelf being cut away adjacent to the entrance to said raceway to 50 allow misplaced rivets to pass into the bottom of said hopper and means constructed and arranged to push said rivet along said casing to the entrance to said raceway.

5. A hopper for feeding a two-pronged rivet having, in combination, a casing with a cylindrical wall and a bottom, a shelf forming a part of said bottom at the base of said 55 wall arranged at an angle thereto and forming a support for a rivet head, the bottom of said hopper being inclined downwardly from said shelf, an annular flange extending partly around the inner face of said wall, there being a space between said flange and shelf into which a portion of the head of said 60

said rivet may project, the inner edge of said flange constituting a guide for the prongs of said rivet, a raceway leading out of said hopper, the bottom of said raceway being a continuation of the top of said shelf and 70 one side of said raceway intersecting the inner edge of said flange, means constructed and arranged to push said rivet along said casing to the entrance to said raceway and a cam adjacent to the entrance to said raceway arranged to engage said pushing means and move the same inwardly on said hopper to disengage said rivet and allow it to slide down said raceway. 75

6. A hopper for feeding a two-pronged rivet having, in combination, a casing with a cylindrical wall and a bottom, a shelf forming a part of said bottom at the base of said wall arranged at an angle thereto and forming a support for a rivet head, the 80 bottom of said hopper being inclined downwardly from said shelf at an angle thereto, an annular flange extending partly around the inner face of said wall, there being a space between said flange and shelf into 85 which a portion of the head of said rivet may project, the inner edge of said flange constituting a guide for the prongs of said rivet, and a raceway leading out of said hopper, the bottom of said raceway being a continuation of the top of said shelf and one side of said raceway intersecting the inner edge of said flange, one end of said flange forming a part of one side of said raceway and projecting into said hopper beyond the opposite side of said raceway. 90

7. A hopper for feeding a two-pronged rivet having, in combination, a casing with a cylindrical wall and a bottom, a shelf forming a part of said bottom at the base 100 of said wall arranged at an angle thereto and forming a support for a rivet head, the bottom of said hopper being inclined downwardly from said shelf at an angle thereto, an annular flange extending partly around 105 the inner face of said wall, there being a space between said flange and shelf into which a portion of the head of said rivet may project, the inner edge of said flange constituting a guide for the prongs of said rivet, a raceway leading out of said hopper, the bottom of said raceway being a continuation of the top of said shelf and one side of said raceway intersecting the inner edge of 110 said flange, a rotary member located in said hopper and a series of laterally flexible fingers projecting downwardly from said rotary member adjacent to said flange, and means arranged to engage said fingers adjacent to the entrance to said raceway and push them inwardly toward the center of said hopper to allow said rivets to slide into and down said raceway. 115

8. A hopper for feeding a two-pronged rivet having, in combination, a casing with 120

a cylindrical wall and a bottom, a shelf forming a part of said bottom at the base of said wall arranged at an angle thereto and forming a support for a rivet head, the 5 bottom of said hopper being inclined downwardly from said shelf, an annular flange extending partly around the inner face of said wall, there being a space between said flange and shelf into which a portion of the 10 head of said rivet may project, the inner edge of said flange constituting a guide for the prongs of said rivet, a raceway leading out of said hopper, the bottom of said raceway being a continuation of the top of said 15 shelf and one side of said raceway intersecting the inner edge of said flange, a rotary member located in said hopper, a series of laterally flexible fingers projecting downwardly from said rotary member adjacent 20 to said flange and a cam on said wall arranged to engage said fingers adjacent to the entrance to said raceway and push them inwardly toward the center of said hopper to allow said rivets to slide into and down 25 said raceway.

9. A hopper for feeding rivets in an inverted position having, in combination, a casing with a cylindrical wall and an inclined bottom, a raceway leading out of 30 said hopper at the bottom of said wall, there being a guide slot at the bottom of said wall and a shelf located partly beneath said slot and forming a support for the heads of said rivets, the bottom of said hopper being inclined toward the center of said hopper at 35 an angle to said shelf, the bottom of said raceway being substantially a continuation of the top of said shelf.

10. A hopper for feeding rivets in an inverted position having, in combination, a casing with a cylindrical wall and an inclined bottom, and a raceway leading out of 40

said hopper at the bottom of said wall, there being a guide slot at the bottom of said wall and a shelf located partly beneath said slot 45 and forming a support for the heads of said rivets, the inner face of said wall adjacent to said slot constituting a guide for the prongs of said rivets, said guide face of said wall at one side of the entrance to said raceway 50 extending inwardly toward the center of said hopper beyond the guide face of said wall on the opposite side of the entrance to said raceway.

11. A hopper for feeding a two-pronged 55 rivet having, in combination, a casing with a cylindrical wall and a bottom, a shelf forming a part of said bottom at the base of said wall arranged at an angle thereto and forming a support for a rivet head, the bottom of 60 said hopper being inclined downwardly from said shelf at an angle thereto, an annular flange extending partly around the inner face of said wall, there being a space between said flange and shelf into which a portion of the head of said rivet may project, the inner edge of said flange constituting a guide for the prongs of said rivet, and a raceway leading out of said hopper, the bottom of said raceway being a continuation 65 of the top of said shelf and one side of said raceway intersecting the inner edge of said flange, the other side of said raceway opening into a slot provided at the bottom of said wall, said slot constructed and arranged to receive a portion of the head of said rivet.

In testimony whereof I have hereunto set my hand in presence of two subscribing witnesses.

ARTHUR R. HAVENER.
